FIG. 6.

Inventor John N. Reese
by Henry Orth # UNITED STATES PATENT OFFICE.

JOHN NICHOLAS REESE, OF YOUNGSTOWN, OHIO.

CHARGING DEVICE.

1,217,219.

Specification of Letters Patent. Patented Feb. 27, 1917.

Application filed November 29, 1915. Serial No. 64,054.

To all whom it may concern:

Be it known that I, JOHN NICHOLAS REESE, a citizen of the United States of America, residing at Youngstown, Mahoning county, Ohio, United States of America, have invented certain new and useful Improvements in Charging Devices; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to blast furnace charging devices of the type in which a skip discharges into a distributing chute that delivers the skip load onto a charging bell of the furnace.

The chute is rotated from the skip, either when the skip ascends or descends, or otherwise according to the requirements of the plant.

The object of my invention is to improve devices of this type and obtain a better and more accurate distribution of the charge on the bell.

To this end I change the angle of inclination of the chute, make the chute V-shaped in section, and have the side walls converge toward the lower discharge end, so that, no matter how large or how small a quantity of material is delivered to the chute by the skip, the material will be discharged onto the main bell toward a vertical axial plane through the chute for the particular discharging position.

Another object is to automatically close the top of the hopper when the main bell is dropped to discharge the distributed skip loads into the furnace, and this is preferably done from the bell beams. The chute is rotatable beneath and independently of the closure.

Other details of construction will herein-after be more particularly described and claimed.

In charging devices provided with chutes with which I have had experience, the furnace has worked very irregularly, and after a considerable time I came to the conclusion that the charging of the furnace was not correct, as that part of the furnace opposite the skip received a considerably larger portion of every charge than that part of the

furnace next to the skip. I also found that in nearly every case the center of gravity of the skip load when placed on the bell was not in the position it was intended it should be.

The problem of remedying these defects was a difficult one, especially as it was impossible to determine at once what was the initial cause of the variations.

I have discovered that the centers of gravity of the piles were too close to the hopper and that by placing them closer to the apex of the bell this would overcome the irregular placing of the piles by lessening the distance they could be displaced from their proper positions.

I also found that by converging the walls of the chute and making it V-shaped, the charge could be placed on the bell where intended. The irregularity in the operation of the furnace was entirely overcome, and there has been no trouble since.

In the accompanying drawings I have shown a structure embodying my invention, and in said drawings—

Figure 1 is a vertical, central section of so much of a blast furnace top as is necessary to illustrate my invention;

Fig. 2 is a plan view thereof.

Fig. 3 is a top view of the distributor chute.

Fig. 4 is a bottom view thereof.

Fig. 5 is a sectional detail showing the manner of securing the chute to the rotating ring or mouth portion.

Fig. 6 is a diagrammatic view showing the bell and hopper and the skip discharging into the distributor.

The sheet metal casing or gas seal for the furnace is extended above the top of the brick-work of the furnace and platform in a cone 1, as is customary with some furnace tops. The casing is supported by the customary structural iron frame work 2.

At the top of the cone 1 and surrounding the opening in its top is a ring 3 on which slides a ring 4 forming the base of the chute mouth 5. The ring 4 is provided with a depending flange 4^a and an internal seat 4^b. The flange 4^a holds the flaring, enlarged mouth 5 in position and prevents it from slipping off of ring 3 during rotation.

Bolted to the flange is the circular rack 6, by which the chute is rotated, the mechanism for rotating it being that customarily used, to which no claim of novelty is made by me.

Grease cups are distributed over ring 4, and supply grease to the contacting surfaces of rings 3 and 4.

Carried by and resting on the seat 4^c is the 5 external flange of the chute 9 held to the chute mouth 5 by means of pins 10, Fig. 5, engaging recesses or notches 11. The chute tapers toward its lower end, Fig. 3, the sides 9^a converging to form a V-shaped opening 12 that discharges onto the bell b of the 10 blast furnace.

As will be observed from the drawing, the upper end of the chute body 9 has a conical entrance portion c that is supported in the 15 conical mouth 5. The bottom wall 13 of the chute is a continuation of the conical entrance portion c and of the same shape. At the front, opposite the rear wall 13, the conical entrance portion c joins a cylindrical portion d, from which portion of the chute 20 extends a tapering eccentrically arranged elongation that is V-shaped in section and whose flat sides 9^a produce a cross section whose area diminishes toward the smaller 25 V-shaped lower end 12.

The angle of the axis of the chute to which the bottom wall 13 is substantially parallel, has been increased from 45° to about 63°, so as to make a steeper incline, this incline being 30 determined by the position of the apex of the bell and the crosshead supporting the bell.

The chute is caused to rotate after each 35 discharge of the skip s, usually during the descent of the skip through an angle of about 86° 38' 30", and after four or eight skip loads have been deposited the bell is lowered to discharge into the furnace.

The bell is lowered by the bell beams 14 40 pivoted at 14^a. Each beam has a rod 15 depending therefrom, which rod passes through the casing 1 and both rods are connected to a cross head 16 beneath the chute 9, from the middle of which cross head the bell is suspended. The distance between the two rods 45 15 is sufficient to permit the rotation of the chute under all conditions of operation.

Over the chute is a stationary sheet metal 50 cover 17 having an opening therein closed by a door 18 mounted on hinges 19 on the cover 17. Extending across and mounted on the door is a beam 20. The ends of this beam 20 extend beyond the sides of the cover 17 into the path of the bell beams 14, and carry 55 anti-friction rollers 21.

The ends of the bell beams 14 are provided with cams 22 arranged to engage the rollers 21 when the bell is raised to close the hopper.

60 The operation is as follows:

When the bell is raised the cams 22 on the ends of the bell beams 14 engage the rollers 21 and raise the door 18. The skip ascends and dumps its charge into the chute 65 mouth 5, and by gravity it descends onto the

bell. If the chute is positioned so that its bottom wall 13 is in line with or parallel to the skip bottom when in discharging position, i. e., 180° from the position shown in Fig. 6, the skip charge passes through the 70 chute in a straight line, the converging sides of the chute and its V-shape causing the charge to compact or hold together and neatly deposit itself in a pile on the bell with its center of gravity in the vertical 75 axial plane of the chute.

Should the chute be directed transverse to the line of discharge of the skip, the charge 80 will be deposited on or toward the far wall of the chute, and in descending the converging chute walls and V-shaped cross section will compel the charge to deposit on the bell in the vertical axial plane of the chute, instead of to one side thereof, which has been 85 the trouble with chutes of other shape.

I claim—

1. In a blast furnace charging device having a hopper and a coöperating bell, the combination with the bell and hopper thereof, of a chute rotatably mounted above said bell and hopper and arranged to discharge thereon, said chute having an enlarged mouth located centrally of said bell and hopper, and a smaller, eccentrically arranged V-shaped discharge end, the sides of 95 said chute converging to said smaller end and the bottom wall of said chute making an angle of approximately sixty-three degrees with a horizontal.

2. In a blast furnace charging device having a hopper and its coöperating bell, the combination with the bell and hopper thereof, of a chute having a mouth arranged centrally with respect to said bell and hopper and having a prolongation rigid therewith 105 and extending eccentrically therefrom and having a V-shaped discharge end discharging onto said bell.

3. The combination with a blast furnace, the cover and the charging bell; of a rotatable chute mounted above said bell having a centrally arranged mouth and a downwardly projecting discharging portion rigid therewith and tapering to a V-shaped contracted end eccentric to said cover.

4. In a blast furnace charging device, the combination with a cover, a hinged charging door on the cover; of bell beams, and means to permit the automatic opening and closing of said door by the action of said 110 beams on a part of the door.

5. In a blast furnace charging device, the combination with a rotatable charge directing chute; of a stationary cover therefor, a hinged door on the cover, bell beams, cams 125 on said beams, and rollers on said door arranged for engagement by said cams when the beams are operated.

6. In a blast furnace charging device, the combination with the blast furnace and its 130

charging bell; of a rotatable chute above said bell for discharging a partial charge onto the bell and having an inclination of approximately sixty-three degrees with a horizontal.

7. In a blast furnace charging device, the combination with a cover, a hinged charging door on the cover and bell beams operating as cams to cam the door to open position 10 when their bell is raised.

8. In a blast furnace charging device, the combination with the charging bell of said device; of a rotary chute arranged above said bell and having a circular conical mouth and an inclined body whose bottom extends from said mouth to a contracted V-shaped end, the slope of said bottom being substantially a straight continuation of the line of slope of said body.

9. A removable chute body having a circular conical entrance portion and an eccentric elongation V-shaped in cross-section, the cross-sectional area of which decreases toward its discharge end.

10. A removable chute for blast furnace tops having a circular, conical, substan-

tially horizontally disposed mouth merging into a tapering, downwardly inclined straight extension having substantially plane walls at its contracted discharge end 33 at an angle to one another to form a V-shaped discharge opening eccentric to said mouth.

11. In a blast furnace charging device, the combination with a cover, and a hinged 35 charging door on the cover; of pivoted bell beams whose bell supporting ends engage the door to open and close it.

12. In a blast furnace charging device, a circular conical mouth having means for detachably securing it to a furnace top, a chute body having a conical entrance portion seated in said mouth and provided with an eccentric elongated V-shaped extension of the same inclination as the entrance portion. 40 45

In testimony that I claim the foregoing as my invention, I have signed my name in presence of two subscribing witnesses.

JOHN NICHOLAS REESE.
